Howard S. Smith
ATTORNEY.

UNITED STATES PATENT OFFICE.

JAMES A. WILES, OF HAMILTON, OHIO.

STORAGE-BATTERY-TERMINAL FULLER.

Application filed March 26, 1928. Serial No. 264,812.

This invention relates to new and useful improvements in storage battery terminal pullers.

It is well known that when a terminal corrodes on the post of a storage battery, it is very difficult to remove and rough handling methods must be employed to remove it. Bars and other instruments used for this purpose dent and otherwise injure the battery.

It is therefore the object of my invention to provide a screw device which may be conveniently applied to a corroded storage battery terminal for the purpose of removing it from a post with ease.

The device is extremely flexible and is easy to manufacture and assemble.

In the accompanying drawings illustrating my invention, Figure 1 is a top plan view of my terminal puller applied to the terminal of a storage battery. Figure 2 is a side view of the same. Figure 3 is an end view thereof. Figure 4 is a sectional view taken through the terminal puller itself on the line 4-4 of Figure 1. And Figure 5 is a sectional view taken through the puller on the line 5-5 of Figure 2.

Referring to the accompanying drawings for a detailed description of my invention, the numeral 1 designates a screw holding member that is preferably a casting which is formed with a screw hole in its reinforced central portion. At one end the casting 1 is channeled as shown in Figure 5 to provide ledges 2, 2 over which the hook ends 3, 3 of eyelets or arms 4, 4 respectively fit. (See Figures 3 and 5.)

The eyelets 4, 4 are put under an inward tension by the following means. Formed in the upper end of each eyelet is a hole through which a screw 5 is freely inserted for entrance into a threaded hole in the side of the channeled portion of the member 1. Surrounding each screw 5 between its head and the member 4 is a coil spring 6 that exerts an inward pressure upon its respective eyelet for a purpose to be hereinafter described.

Inserted in the screw hole in the thickened central portion of the casting 1 is a screw or stud 7 formed with an outer wrench receiving head 8. On its inner end the screw 7 carries a swivel cap 9 to engage a battery post 10 of a storage battery 10a. This cap 9, which does not turn when it is pressed against an object, will prevent the screw 7 from boring

into the post when rotated to pull a terminal from the latter.

Formed in the rear end of the member 1 is a hole which freely receives the upper threaded end of a swivel hook 11. On the hook end of the latter there is formed a tooth 12 which is adapted to firmly engage a round cable-receiving end 13 of a storage battery terminal 14 applied to the post 10. Applied to the upper threaded end of the swivel hook 11 is a knurled cap nut 15.

My improved pulling device may be applied in the following manner to any battery terminal, such as the terminal 14, that has corroded on the post 10.

The terminal 14 carries the conventional clamping bolt 16 and nut 17. Over the head of the bolt and the nut the eyelets 4, 4 are fitted by first springing one eyelet 4 over the threaded end of the bolt and the other eyelet over the head end of the bolt. These eyelets or arms are free to be moved in any direction against the tension of the springs 6, to permit them to be easily applied to the bolt ends of any storage battery terminal. When the screw 7 is turned to remove the terminal from the post on which it has corroded, the force of the pull of the eyelets is borne by the channeled end of the member 1 over which the ends of the eyelets hook, and not by the screws 5 which merely support the springs.

The toothed swivel hook 11 is engaged with the cable-receiving part 13 of the terminal 14 in the manner shown in Figure 2, after which the nut 15 is screwed down upon the threaded end of said hook.

The middle screw 7, which can be seen from any angle, is now ready to be turned to force its swivel cap 9 against the post 10. When the screw 7 is so turned by a wrench applied to its head 8, it will easily lift the terminal 14, engaged by the eyelets 4 and hook 11, from the post 10. The lifting operation is thus performed without injury to the terminal, the post or the battery. When a bar or other heavy instrument is used for this purpose, the battery is often severely marred.

It will be observed that the pulling arms or eyelets 4 are at an angle of about thirteen degrees. Therefore, the holes in them will be at the same angle, thus forming a tooth or claw of the lower part of the hole. These teeth or claws increase their grip as pressure from the screw 7 is applied.

When the pulling operation has been ac-

complished, the device may be easily removed from the terminal by unloosening the hook 11 and spreading the eyelets 4.

Having described my invention, I claim:

- 5 1. A device of the type described for pulling a terminal from a storage battery post, comprising a screw holding member formed with a central screw hole, a screw in said hole adapted to engage said post, swivel eyelets 10 secured to one end of said screw holding member, at an angle to each other, for application to one end of said terminal, and a swivel hook secured to the other end of said screw holding member for engagement with the other end 15 of said terminal, said eyelets and hook adapted to pull the terminal from said post when the pressure of the screw is applied to the latter.
2. A device of the type described for pulling a terminal from a storage battery post, 20 comprising a screw receiving member formed with a central screw hole, a screw in said hole adapted to engage said post, means secured

to the rear end of the screw member for engaging the terminal, a pair of hook eyelets 25 suspended from the front end of said member, and tension means for forcing said eyelets toward each other for the purpose specified.

3. A device of the type described for pulling a terminal from a storage battery post, comprising a screw-receiving member formed with a central screw hole, a screw in said hole for engagement with said post, means on the rear end of the screw member for engaging 30 one part of said terminal, a pair of hook eyelets suspended from the front end of the screw member, each eyelet formed with a hole in its upper portion, a screw projecting through said hole in each eyelet into the screw member, and a spring surrounding each screw between its head and the screw member for the purpose specified.

In witness whereof I have hereunto set my hand this 24 day of March, 1928.

JAMES A. WILES.
